(57) **CLAIM**

I claim the ornamental design for a beam projector, as shown and described.

DESCRIPTION

FIG. 1 is a top perspective view of a beam projector showing my new design;

FIG. 2 is a front view thereof;

FIG. 3 is a rear view thereof;

FIG. 4 is a left side view thereof;

FIG. 5 is a right side view thereof;

FIG. 6 is a reduced top view thereof; and,

FIG. 7 is a bottom view thereof.

The portions of the beam projector shown in broken lines form no part of the claimed design.
